UNITED STATES PATENT OFFICE.

HERBERT WILLIAM HALL, OF ZURICH, SWITZERLAND.

APPARATUS FOR EMPTYING SUPERPHOSPHATE REACTION-CHAMBERS.

1,232,295.

Specification of Letters Patent.

Patented July 3, 1917.

Application filed February 6, 1915. Serial No. 6,569.

To all whom it may concern:

Be it known that I, HERBERT WILLIAM HALL, engineer, a citizen of the Republic of Switzerland, residing at Zurich, in the 5 Canton of Zurich, Republic of Switzerland, have invented a new and useful Apparatus for Emptying Superphosphate Reaction-Chambers, of which the following is a specification.

10 My invention relates to improvements in apparatus for emptying superphosphate reaction chambers by means of a transportable, rotating scraping machine, running on rails and comprising a trolley carrying an 15 electric motor for driving the cutters only, while the advance is not effected by motor power, but by gravity. The principal object of the invention is the possibility of emptying reaction chambers of rectangular 20 or cylindrical form, the former being of almost general use at the present time, without costly alterations to an existing plant, and the possibility of using a transportable, rotary machine of very simple design. 25 Transportable machines provided with a change of direction for forward self-movement into the chamber and backward self-movement out of same, necessitate the use of complicated automatic reversing apparatus. 30 It is generally known, that such transportable machines require constant repair, as their iron parts become corroded in a very short time, the finer parts of the electrical apparatus being soon ruined by the 35 vapors of sulfuric acid and the high temperature in the chamber. In the above-mentioned simple machine the electric motor and the speed reducing gear can be completely covered and easily protected 40 against the injurious vapors of sulfuric acid.

To allow the chamber to be emptied by such a simple machine, I make use of a tilting track for the same, to be erected in the chamber. An easy working of the machine will not be obtainable, if the scraped material is allowed to reach the surfaces of the rails, and grease the same, and adhere to the wheels. The wheels then being no longer truly round and being pasted 45 with more or less thick layers of superphosphate, cause the machine to advance irregularly, in consequence of which the scraped material will vary in thickness. It may also happen, that the machine running 50 obliquely on the track and sticking between the rails, is brought to a standstill. It will

therefore be necessary to dispose the running surfaces for the wheels in such a way, that they are out of reach of the scraped material. The tilting track has besides the 60 great advantage, that the angle of inclination can be determined in conformity with the dryness of the superphosphate in the chamber, so that the thickness of the scraped material can be varied at will. 65

The accompanying drawing represents a tilting track arrangement in a reaction chamber, in accordance with the present invention. Figure 1 shows a longitudinal section and Fig. 2 a cross section through one 70 half of a double chamber of the ordinary rectangular form.

Fig. 3 is a face view of the rotary scraper.

Fig. 4 is mainly a sectional view illustrating the motor and the gearing operatively 75 connecting it with the scraper.

The brick chamber *a* is charged by the disintegrating vessel *b* on the middle wall, *c* is a door, through which the scraping machine can enter into the chamber, the scraped 80 material falls through slits *d* at the bottom. *e* is the tilting track, substantially consisting of two channel irons and end brackets, the upper parts of the lower flanges of the channel irons being the running surfaces, 85 are thus disposed out of reach of the scraped material; the track is prolonged outside the door to allow the machine to be shunted on. *f* is an inlet for fresh air, to be opened when the chamber is being emptied. *g* is a 90 flue connected with the interior of the chamber and serving to conduct the gases to a chimney. *h*, *h* are two tilting-bearings, common to various tilting contrivances. Half of the bearing bolt is embraced by the upper 95 part of the body, which is bolted to the track *e*, the other half by the lower part, which is bolted to the foundation wall *i*. Dotted lines *k*, Fig. 2, represent the scraping machine, which may be variously constructed, but is preferably provided with a series of rotary cutters operated by an electric motor as illustrated in Figs. 3 and 4. Before the chamber is filled, the track *e* is tilted upward in direction of *A*, pasted at 100 the sides with greasy superphosphate against the fixed boards *l* and its upper surface covered with movable boards *m*, the latter similar to those, which served for covering the bottom slits *d* of the chamber, before the 105 track was put in.

As is well known, the chambers are not

filled more than 5 to 6 ft. high, when they are emptied by hand, on account of the danger for the workmen to be buried beneath the falling top masses of the superphosphate, when the block is undercut. When my tilting track is used in combination with the scraping machine, nothing prevents the chamber to be filled almost up to the air inlet *f*. The volume of the mass cut out by the scraping machine, will in most cases be near the contents of the chamber, when filled only 5 to 6 ft. high.

When the superphosphate is sufficiently dried in the chamber, the door *c* is opened, the track *e* tilted down to its level position, the movable boards *m*, which get loosened from the block at the same time as the track, are taken out, the machine shunted on the part of the track projecting outside the door and the motor driving the cutters, put in action. In accordance with the dryness of the superphosphate, the track is then tilted upward just so much as to allow the machine to run down the inclined track by the action of the component of its own weight and to cut the material in the desired thickness. During its forward movement the machine will cut out of the block a cylinder having an inclined axis *B* parallel with the running surface of the track and open on the top and at the bottom, while the scraped material falls through the bottom slits *d* on a mechanical conveyer *n*. The remaining parts *o* and *p* of the superphosphate are not taken out but left permanently in place. The part *q* at the back wall likewise remains in the chamber, and the ma-

chine, after having performed its work, is pulled out of the chamber by hand, in backward direction.

The tilting track as above described, is likewise applicable to a horizontal reaction chamber of cylindrical form *i. e.* of circular section, when the chamber is provided with slits at the bottom to allow the scraped material to fall down on mechanical conveyers. For a section of a given inside diameter it will only be necessary, on account of the inclined axis of the cylinder cut out by the machine, to have the diameter of this cylinder correspondingly smaller.

I claim:

An apparatus for emptying superphosphate reaction chambers, comprising a receptacle for the superphosphate, said receptacle having an opening extending longitudinally through its lower wall, a track pivoted at its inner end and adapted to have a tilting movement in a vertical plane in said opening, means supported by said track for closing the opening and for protecting the track from the superphosphate, and a scraping machine adapted to travel on said track, the track being adapted to be lowered to permit the removal of the covering means and to allow the scraping machine to be shunted thereon and then lifted to cause the machine to feed by gravity as the grinder operates.

Dated this 15th day of January, 1915.
HERBERT WILLIAM HALL.
